OF D 5.272

UNITED STATES PATENT OFFICE.

JOSEPH MILLER CHRISTIE, OF KIDDERMINSTER, ENGLAND, ASSIGNOR TO HENRY JECKS DIXON & SONS.

DESIGN FOR A CARPET-PATTERN.

Specification forming part of Design No. 5,272, dated September 19, 1871.

To all whom it may concern:

Be it known that I, JOSEPH MILLER CHRISTIE, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of this specification.

The nature of my design is fully represented in the accompanying photographic illustration, to which reference is made.

I claim as my invention—

The design for carpets, as shown.

JOSEPH MILLER CHRISTIE.

Witnesses:

JAMES MORTON,
Solicitor, Kidderminster.
